(57) **CLAIM**

The ornamental design for a motor housing with propulsion unit, as shown and described.

DESCRIPTION

FIG. 1 is a front and right side perspective view of a motor housing with propulsion unit, showing my new design, with a right-hand side flap being closed;

FIG. 2 is a front and left side perspective view rear view thereof, with a left-hand side flap being closed;

FIG. 3 is a rear and left side perspective view rear view thereof, with the left-hand side flap being closed;

FIG. 4 is a rear and left side perspective view rear view thereof, with the left-hand side flap being open;

FIG. 5 is a front perspective view thereof, with the left-hand side flap being open;

FIG. 6 is a rear perspective view thereof, with the left-hand side flap being open;

FIG. 7 is a top, rear and right side perspective view rear view thereof;

FIG. 8 is a front perspective view thereof, with the left-hand and right-hand side flaps being open;

FIG. 9 is a left side and front perspective view thereof; with the left-hand side flap being open; and,

FIG. 10 is a right side and front perspective view thereof; with the right-hand side flap being open.

The portions of the motor housing with propulsion unit that are shown in broken lines form no part of the claimed design.

1 Claim, 10 Drawing Sheets
